TWO-STROKE INTERNAL-COMBUSTION ENGINE

Fernand Chave, Casablanca, French Morocco

**Application December 21, 1945, Serial No. 636,305
In French Morocco February 2, 1945**

1 Claim. (Cl. 123—74)

1

This invention relates to two strokes internal combustion engines and has for its primary object to provide an engine of this type of specially improved construction adapted to prevent any induction of the gaseous or explosive mixture into the crankshaft casing containing the lubricating oil sump and therefore any contamination of said oil by said gaseous mixture and the consequent loss of its lubricating qualities.

Another object of the invention is to provide an internal combustion engine as aforesaid wherein the piston is slidably housed in a compression and power chamber space defined between the cylinder head and a stationary one-piece obturator or diaphragm adapted constantly to isolate off said space from the crankshaft casting.

A further object of the invention is to provide an internal combustion engine of the aforesaid type which while possessing the aforesaid advantages lends itself to easy structural adaptation into engines having their cylinders arranged in straightline or V or star formation.

A still further object of the invention is to provide a two stroke internal combustion engine made up of a minimum number of parts of rugged structure capable of being readily made and assembled at cheap material and labor costs and utilisable either for propelling vehicles or for stationary uses.

With these and such other objects in view as will incidentally appear hereafter, the invention comprises the novel construction and combination of parts that will now be described in detail with reference to the accompanying diagrammatic drawing exemplifying the same and forming a part of the present disclosure.

In the drawing:

Fig. 1 is partly an elevational view and partly a vertical sectional view of the improved engine showing the piston in the cylinder and the stationary obturator or diaphragm closing the upper piston-receiving chamber at its lower end.

Fig. 2 is a view similar to Fig. 1 showing the piston at the upper end of its stroke.

Fig. 3 is a separate view of the piston shown partly in elevation and partly in vertical section.

Fig. 4 is a view similar to Fig. 3 taken at right angles thereto.

Fig. 5 is a view partly in elevation and partly in vertical section of the one-piece and portless bell-shaped diaphragm or obturator isolating off the compression and power chamber space from the crankshaft casing.

Fig. 6 is a top plan view of the bell-shaped obturator or diaphragm.

Fig. 7 is a view partly in elevation and partly in vertical section of the bell-shaped obturator taken at right angles to Fig. 5.

As shown, 1 designates the engine cylinder 5 the upper portion of which is provided with an upstanding internally screw-threaded stub pipe 2 adapted to receive an ignition element such as a spark plug (not shown). The cylinder 1 has one of its side walls formed integrally with a hollow bulge 3 forming a by-pass duct for the gaseous mixture, said cylinder wall having a pair of superimposed ports leading into said by-pass duct. The cylinder is formed in its opposite side wall with a pair of vertically spaced ports 4, 5. 10 15 The lower end of the cylinder 1 is provided on each side with an elongated bulge 6, 7 (see Fig. 2) whose wall merges with that of the casing for the crankshaft (not shown) which is revolutely supported in bearings as usual and is linked with the piston through a connecting rod 8 having its 20 small end hinged to a wrist pin 9.

The lower end of the cylinder 1 is provided with a flange 10 to which is abutted the lower flange 11 of a one-piece and portless bell-shaped obturator or diaphragm 12 the upper portion of which has grooves 13 adapted to receive piston rings (not shown) of conventional structure. The obturator flange 11 has a plurality of holes 14 adapted to receive pins, bolts or the like for firmly securing together the cylinder and bell-shaped obturator unit and the crankshaft casing to form a rigid assembly. As illustrated in Fig. 5, the obturator 12 is provided with a pair of top chamfers 15 defining passages for the flow of the gaseous mixture. A pair of slots 16 are also provided to permit free passing of the piston portion carrying the wrist pin bosses. The obturator 12 also has a pair of slots for the piston axis.

The function of the one-piece and portless bell-shaped obturator 12 is to isolate off the crank-shaft casing from the chamber defined inside the piston. The particular dome formation of the obturator permits a very high compression rate of the inlet gases to be achieved, while its unitary character promotes cooling of its face which contacts the explosive gases.

The engine piston 18 is advantageously made of thin steel in order to possess proper lightness and strength and is slidably housed between the outer wall of the obturator 12 and the inner wall of the cylinder 1. The top surface of the piston 18 is provided with a deflector 19 adapted to deviate the gaseous mixture led into the explosion chamber and to direct it towards the upper portion of the cylinder so as to enable the same to scavenge said chamber from burnt gases. Slightly before its top end, the piston 18 is formed

with grooves 20 (the number of which may vary to suit constructional requirements) adapted to receive conventional gasket rings (not shown). Slightly under the grooves 20, the piston 18 has a port 21 through which the gases may flow to the by-pass duct 3. On its opposite side and at a level lower than that of the port 21 the piston 18 has a further port 22 for the induction of gases which arrive through the inlet port 5 in the cylinder 1.

The lower end of the skirt of the piston 18 has a pair of bosses 23, 24 adapted to receive the wrist pin 9 for the connecting rod 8. The bosses 23, 24 are received in the cylinder bulges 6, 7, thereby ensuring better lubrication. A pair of slots 25 (Fig. 4) permit the piston 18 to slide along the obturator 12 without providing a complete cut (see 26 in Fig. 6).

The operation takes place as follows:

The engine works according to the general operative principles of two stroke internal combustion engines so far as gas induction and exhaust are concerned. However, the gaseous mixture never gains access to the crankshaft casing as in prior constructions so that it cannot contaminate and spoil lubricating oil which forms a sump in said casing. As the piston 18 reaches its upper dead centre (as shown in Fig. 2) vacuum prevails in its inner chamber, whereby the gaseous mixture is drawn in through the ports 5 and 22 which are then in coincidence. As the piston reaches its lower dead centre, the gaseous mixture is compressed between it and the bell-shaped obturator 12, while the port 4 is unmasked (as shown in Fig. 1) and the port 21 in the piston coincides with the lower port for the by-pass duct 3 whose upper port is simultaneously uncovered. The gaseous mixture compressed inside the piston 18 is then led to the explosion chamber situated on the top thereof and drives out the burnt gases from the previous explosion, thereby fulfilling a scavenging action and is then compressed inside the explosion chamber, whereupon said gaseous mixture is ignited by the spark which owing to proper timing of the ignition means is then produced between the electrodes of the spark plug carried in the plug pipe 2.

It will be understood that owing to the improved structure of the engine and as the rate of compression of intake gases is higher than in an ordinary two stroke engine, their induction into the explosion chamber is more rapid. The scavenging action on burnt gases is also more complete, so that the general efficiency and running conditions of the engine are improved. Furthermore the elimination of any oil entrained by the gasous mixture means a twofold economy for proper carburation. The engine being of simple structure can be easily built from parts lending themselves to mass production.

Another advantage of the improved engine is that since the crankshaft casing is entirely isolated from the spaces through which the gaseous mixture travels it can be built to form a single hollow structure throughout the length of the engine irrespective of the number of its cylinders.

As above stated, the assembly comprising the cylinder, piston and isolating obturator may be duplicated or multiplied to any extent so as to provide multi-cylinder engines working on the two stroke principle and having their cylinders arranged either in straightline formation or in

V formation or in star formation while preserving the general advantages derived from the structural principles of the engine and the provision of the gas-tight obturator in each cylinder. Where the cylinders are arranged in star formation, a pump should be provided to create suction in the bottom portion of those obturators belonging to downwardly extending cylinders, as will be understood from those skilled in the art.

10 Cooling of the engine may take place either by water or by air, for example owing to the provision of fins or gills on the outer surface of each cylinder.

15 Minor constructural details may be varied without departing from the scope of the subjoined claim.

What is claimed is:

In a two-stroke internal combustion engine having a crankshaft, a frame defining a casing 20 for said crankshaft, a cylinder mounted on said frame, the lower end of said cylinder and the said casing having a pair of diametrically opposed outward elongated bulges thereon, a hollow piston extending to form a skirt and reciprocable within said cylinder, a rod and wrist pin connecting said piston and crankshaft, a pair of flanges on said skirt extending downwardly therefrom, a pair of diametrically opposed hollow bosses on said flanges for receiving said wrist pin, said bosses reciprocable in and guided by the elongated bulges on said cylinder and casing, an inlet port located in said cylinder, an exhaust port located in said cylinder above said inlet port, a hollow bulge rigid with said cylinder forming a bypass, one port of which is in the cylinder wall diametrically opposite the exhaust port and the other port of which is in the cylinder wall diametrically opposite the inlet port, a first port in said piston skirt near its lower end, which port when said piston is at the top of its stroke coincides with the inlet port in the cylinder wall, a second port in the piston skirt near its upper end which port when said piston is at the bottom of its stroke coincides with the lower port of the bypass duct in the cylinder wall, the upper port of the bypass duct and the exhaust port in the cylinder wall both open to the area above the piston when the piston is in the lower said position, and a one-piece portless bell-shaped obturator rigidly held by said casing and tightly separating said casing from the space in which said piston reciprocates, said obturator having a chamfered top face and recesses in its side walls opening downwardly to permit reciprocation of said wrist pin.
